COMBINATION RUBBER DIE

Lewis E. Walton, West Lawn, Pa.

Application June 23, 1941, Serial No. 399,339

6 Claims. (Cl. 113—44)

This invention relates to an apparatus for shaping sheet metal and other material, in the nature of a combination rubber die, and embodies certain modifications of the structure shown in my original application relating to a Combination hydraulic and rubber die, filed April 15, 1941, Serial Number 388,707.

One of the important objects of this invention is the production of a simple and efficient die wherein metal parts may be formed by means of a stationary punch mounted on a post or stake working in conjunction with a rubber bag under pressure or a solid rubber pad under tension.

A further object of this invention is the production of an efficient die having means for regulating the tension on the yieldable shape-forming element.

Other objects of the present invention will appear throughout the following specification and claims.

In the drawings—

Figure 1 is a vertical sectional view through the die;

Figure 2 is a fragmentary sectional view illustrating the manner of forming or shaping the metal parts;

Figure 3 is a vertical sectional view illustrating a modified form of the invention;

Figure 4 is an enlarged sectional view illustrating a modified form of device for connecting the pressure supply line to the flexible pressure bag;

Figure 5 is a vertical sectional view of a further modified form of the invention;

Figure 6 is a vertical sectional view through a still further modified form of the invention;

Figure 7 is a vertical sectional view through still another modified form of the invention;

Figures 8 to 13 inclusive, are various views showing different formations which may be formed by means of specially designed dies.

By referring to the drawings, it will be seen that 15 designates the lower housing of the die which is preferably anchored or secured to a suitable support and is provided with a compartment 16 in which is supported a centrally located vertically extending stake or post 17. This post 17 is secured to the bottom of the lower housing 15 by means of an anchor screw 18. A piston washer 19 of suitable design is slidably mounted within the compartment 16 and upon the post or stake 17, in the manner shown in Figure 1. A steel piston plate 20 rests upon the piston washer 19 and the post 17 extends therethrough. A suitable punch or die member 21 is supported by the post 17, in

the manner shown in Figure 1. An upper movable housing 22 is used in association with the lower housing 15 and is mounted upon a ram of a press in a suitable manner. This upper movable housing 22 is provided with a compartment 23 which contains a rubber inflatable bag 24. A nest plate 25 is adapted to rest upon the steel piston plate 20 and an armor plate 26 is carried by the plate 25, the edges of the plate 26 being turned downwardly, as at 27. The punch or die member 21 extends through the nest plate 25 and the armor plate 26. A sheet 28, which is the part to be formed, is adapted to rest upon the punch or die member 21 and is adapted to engage the under face of the inflatable bag 24.

A nipple 29 is carried by the inflatable bag 24 and comprises an externally threaded stem 30 having a flanged lower end 31 which is serrated upon its upper face. A clamping washer 32 is threaded upon the stem 30 and is also serrated upon its lower face to firmly clamp the inflatable bag 24 in engagement with the nipple 29. A retaining sleeve 33 is threaded upon the threaded stem 30 and carries a flange 34 for overhanging the top face of the upper movable housing 22 and clamping the flange 34 against the top wall 35 of the compartment 23, thereby anchoring the nipple in position. The nipple 29 is provided with a port 37, which port may be closed by a plug 39, and the plug 39 may carry a pressure gauge 38, if desired.

The upper movable housing 22 carries a piston 41 which is vertically movable within the compartment 42 of the housing 43, and a threaded plug 44 is threaded into the upper end of the housing 43 for regulating the tension of the spring 45. The spring 45 is interposed between the plug 44 and the piston 41. The piston 41 is adapted to relieve pressure from the bag 24 when the pressure exceeds the tension of the spring 45 and which spring tension may be regulated by adjusting the plug 44.

A rubber cushion or rubber pad, or a pad of other flowable material, as shown in Figure 5, 45 may be substituted for the rubber bag 24 and the nipple stem, clamping washer, retaining sleeve, and other parts connected with the rubber bag, without violating the spirit of the invention.

The compartment 16 communicates with an inlet 46, which inlet 46 communicates with a suitable accumulator 47 for holding liquid or air under pressure. A pressure gauge 48 is carried by the inlet pipe 46 and an automatic relief valve 49 is carried also by this pipe.

The valve 49 is adapted to relieve pressure be-

yond a maximum amount, and may be adjusted in the conventional manner to control the pressure.

The operation of the die is as follows: The upper housing 22 descends with the ram of the press, carrying with it the rubber pad or the bag filled with the proper amount of liquid or air. When the pad or bag contacts the sheet to be formed, the downward movement produces the initial pressure needed to clamp the entire area of the sheet to be formed and thus, acting as a pressure pad, prevent the sheet from wrinkling when the forming takes place. As the housing continues its descent, the parts surrounding the punch 19, 20, 25, 26 and 27, are pushed down against the hydraulic pressure within the compartment 16 and the sheet to be formed takes the shape of the die 21, as shown in Figure 2. The piston 41 and spring 45 provide a means of relieving the pressure within the bag or pad and thereby provide the means of displacing an equivalent area occupied by the die 21.

It should be understood that pressure within the compartment 16 will constitute a yieldable support for the piston 20 due to the fact that the automatic relief valve 49 will relieve pressure from the compartment 16 when pressure above the piston 20 exceeds the pressure in the compartment 16. Consequently the piston 20 will be yieldably supported. In Figure 1 the parts are shown with the pressure not completely applied and in actual practice the sheet 28 will be held between the bag 24 and the armor plate 26, pressure being applied in suitable amounts to the compartment 16 and to the bag 24.

In Figure 3, there is shown a modified type of the invention, wherein a housing 50 is illustrated having a compartment 51 in which is mounted an inflatable rubber bag 52. This bag carries a nipple 53, which nipple also engages a steel protector plate 54 carried by the top of the bag, the edges of which plate contact the side walls 55 of the compartment 51. The platten 56 of the press supports a rest plate 57, which rest plate carries a nest plate 58 and the punch or die member 59 extends through the plates 57 and 58, as shown. The nest plate 58 may be formed of wood, if desired, and the work sheet 60 is adapted to rest upon the punch 59, and is adapted to be engaged by the rubber bag 52. Pressure pins 61 are carried by the punch 59 and are adapted to be engaged by the conventional pressure pad 62 of the press.

The nipple 53 is illustrated in detail in Figure 4, and this nipple 53 comprises a bottom flange 63 and an upwardly extending threaded stem 64, which stem 64 is provided with a port 65. A clamping washer 66 is carried by the stem 64, and this washer 66 is held in place by a clamping nut 67. In the form shown in Figure 4, the rubber bag 52 is folded back around the aperture 68 of the plate 54, and the flange 63 and washer 66 which are provided with serrated faces, engage the rubber bag, as shown in Figure 4, to firmly clamp the rubber bag adjacent the edges of the aperture 68. The port 65 is adapted to be closed by a plug 65a, which plug 65a may, if desired, carry a gauge 65b.

In the form shown in Figure 5, the platten 70 of the press supports a punch 71 which may be actuated by a pressure plate 72 of the conventional type. The punch 71 is provided with an annular flange 73 which works within a pocket 74 formed in the nest plate 75. A die housing 76 is mounted upon the nest plate 75, and is provided with a compartment 77 in which is mounted a

compressible rubber pad 78. The work sheet 79 rests upon the top of the nest plate 75 and upon the punch 71, and this punch 71 may be moved into engagement with the pad 78, thereby causing the work sheet 79 to be formed around the upper end of the punch 71 in the same manner as that shown in Figure 2. A relief plunger 80 is slidably mounted in the upper end of the die housing 76, and this plunger 80 is provided with a retaining flange 81 to limit its downward movement. The plunger 80 contacts the rubber pad 78 and this plunger 80 is engaged by a coil spring 82, the tension of which may be regulated by a threaded plug 83 mounted in the internally threaded neck 84. The plunger 80 will provide a regulated means to permit pressure to be relieved from the pad 78 as the rubber pad 78 is being compressed by movement of the die member or punch 71. As has been noted above, the die can be made to function through a single downward movement of the ram of the press by means of the piston and hydraulic chamber shown in Figure 1—see parts 16, 17, 18, 19, 46, 47, 48 and 49.

By referring particularly to Figure 6, it will be seen that 85 designates a punch-carrying section which carries a die or form 86. A cover plate 87 is carried by the section 85, and a rubber or other flexible diaphragm 88 is clamped between the cover 87 and the section 85. A metal sheet or other work sheet 89 to be formed into the desired shape, rests upon the form or die 86. An inlet line 90 communicates with the compartment 91 above the diaphragm 88 and suitable pressure may be fed thereto and controlled in the same manner as described in the other modified forms. An exhaust pipe 92 communicates with the compartment 91 above the diaphragm 88, and this pipe 92 carries a suitable pressure gauge 93 and an exhaust valve 94. As pressure is fed into the compartment 91, the flexible diaphragm 88 will force the sheet 89 around the form 86 in a manner somewhat similar to that previously described in the other embodiments.

In Figure 7, there is shown a still further modified form of the invention wherein 95 designates the punch-carrying section which supports a die member 96 within the compartment 97. A cover plate 98 is provided which clamps a flexible diaphragm 99 in position within the compartment 97. The beveled guiding blocks 100 are mounted within the section 95 in a position to be engaged by the edges of the plate or sheet 101 which is to be formed around the die member 96. When pressure is admitted through the inlet pipe 102, the sheet 101 will be formed around the die member 96 and the flexible diaphragm 99 will follow the position shown in dotted lines. Since the edges of the sheet 91 contact the beveled faces 103 of the blocks 100, the diaphragm will be prevented from curling under the edges of the plate 101. A suitable outlet pipe 104 is provided similar to the pipe 92 and may also be provided with a suitable gauge and automatic relief valve.

Figures 8 to 13, inclusive, illustrate various forms of dies as examples to indicate the manner in which the metal may be formed around the dies. In forming the type illustrated in Figure 12, two steps are necessary, and after one side has been formed the metal may be inverted and the opposite or reverse folds may be formed in the conventional manner. It should be understood that it is not desired to limit the particular type of form or die so far as the shape is concerned, since various types may be provided without de-

parting from the spirit of the invention, and a great variety of shapes or cross-sections may be produced, depending upon the nature of the specific shape of the die or form used.

By means of the present device, it has been found possible to form weird and seemingly impossible shapes, and it is possible also to perform an unlimited number of operations in one continuous stroke, except the form shown in Figure 12, as explained above. The form shown in Figure 13, which is in the nature of a rail, such as may be used on toy trains and the like, may be easily produced. Also embossing may be provided due to the natural functions of the hydraulic pressure, and an important feature to bear in mind is the fact that the flat sheet is formed by means of the hydraulic pressure acting upon the flexible diaphragm, bag, or rubber sheets. The pressure when properly applied will keep the metal from wrinkling when the metal is being formed in the desired shape, with the result that the flanges which are formed become actually thicker inasmuch as the metal may shrink from a larger circumference to a smaller one. It has been found that the metal will form itself around the unusually shaped dies regardless of the shape or size of the die or form which is used.

It should be understood that although only one die member or punch is shown, any number of die members of various shapes may be used in one unit for forming various articles of different shapes in one operation, because of the yieldable pressure member which co-operates with the die member or punch. Further, it should be understood that the unit or units illustrated may be used in a punch press, or press of any kind which would be capable of bringing the top and bottom housings together, such for instance, as the housing shown in Figures 1 and 2. Figures 3 and 5 illustrate units for use on a double acting press, although both could be adapted to be used on a single-action press. Figures 1 and 2 illustrate a structure which can be mounted on any conventional press which will bring the movable housing 22 and the lower housing 15 together. In this way, the necessity of employing a pressure pad, to bring the die to a stamping or forming position and into contact with the material to be formed, is eliminated. In the form shown in Figure 1, the movable housing 22 is adapted to be bolted to the platen of any press. The purpose of this invention is to produce a unit which may be used upon a conventional inexpensive type crank press, instead of the expensive type of press which is equipped with a hydraulic base and pressure pad, such as has been used heretofore and as is shown in my application Serial Number 388,707, as well as in the modifications shown herein.

In the form shown in Figures 1 and 3, pressure is produced by the action of the upper housing descending, as it is acted upon by the ram of the press. A selected amount of hydraulic or other pressure is forced into the bag (bag 24 and bag 52) through port 37. The port 37 is then closed and the entire shaping function is accomplished by one movement of the punch press. A pressure gauge 38, if desired, may be carried by the plug 39 which is adapted to close the port 37.

It should also be understood that in the forms shown in Figures 6 and 7, an inflatable bag, or layers of rubber, may be substituted for the diaphragms 88 and 99, if desired. Furthermore, conventional mechanical means with automatically acting clamps and springs may perform

the function of the parts 15, 16, 17, 19, 20, 46, 47, 48 and 49, if desired, without departing from the spirit of the invention. One of the important features of the present invention is the compressible member, such as is illustrated, embodying either a rubber member, or layers of rubber strips, or a bag containing hydraulic or other pressure against which the sheet to be formed contacts, thereby forming the sheet in the contour of the die member or punch.

It should be understood that certain detail changes in the construction and arrangement of parts may be employed without departing from the spirit of the invention so long as such changes fall within the scope of the appended claims.

Having described the invention, what I claim as new is:

1. A die of the class described comprising a base, a movable housing cooperating with the base, a die member anchored upon the base, piston-like means slidably mounted upon the die member and adapted to recede into the base, pressure means for resisting inward movement of the piston means into the base, means for automatically relieving pressure from the piston means at a predetermined degree, an inflatable bag carried by the movable housing and adapted to engage a work sheet contacting with said die member, a means for supplying pressure to the inflatable bag, and adjustable pressure-relieving means carried by said movable housing.

2. A die of the class described comprising a base, a movable housing cooperating with the base, a die member anchored upon the base, piston-like means slidably mounted upon the die member and adapted to recede into the base, pressure means for resisting inward movement of the piston means into the base, means for automatically relieving pressure from the piston means at a predetermined degree, an inflatable bag carried by the movable housing and adapted to engage a work sheet contacting with said die member, a means for supplying pressure to the inflatable bag, adjustable pressure-relieving means carried by said movable housing, said inflatable bag being formed of rubber, a nipple having clamping engagement with the bag, and means for connecting a pressure supply line to the nipple.

3. A die of the class described comprising a base, a movable housing cooperating with the base, a die member anchored upon the base, piston-like means slidably mounted upon the die member and adapted to recede into the base, pressure means for resisting inward movement of the piston means into the base, means for automatically relieving pressure from the piston means at a predetermined degree, an inflatable bag carried by the movable housing and adapted to engage a work sheet contacting with said die member for initially clamping the work sheet in engagement with the die member, a means for supplying pressure to the inflatable bag, adjustable pressure-relieving means carried by said movable housing, said adjustable pressure-relieving means comprising a piston member, said movable housing having an aperture for receiving the piston member, the piston member being adapted to contact the inflatable bag, a spring engaging the piston member, and an adjustable plug for threaded engagement with the movable housing for regulating the tension of said spring.

4. A die of the class described comprising a base, a movable housing cooperating with the

base, a die member anchored upon the base, piston-like means slidably mounted upon the die member and adapted to recede into the base, pressure means for resisting inward movement of the piston means into the base, means for automatically relieving pressure from the piston means at a predetermined degree, an inflatable bag carried by the movable housing and adapted to engage a work sheet contacting with said die member, a means for supplying pressure to the inflatable bag, adjustable pressure-relieving means carried by said movable housing, said piston-like means comprising a piston washer, a steel piston member, a nest plate, and a protector armor plate carried by the nest plate.

5. A device of the class described comprising a rigid die member, a movable work-supporting member, a flexible shape-forming member adapted to clamp material in position upon the rigid die member and said work-supporting member through the entire area of the material and to shape material placed between the members, means for applying pressure upon the flexible shape-forming member to shape material placed between the members, said movable work-supporting member being adjacent the die member for supporting work placed between said die member and said flexible shape-forming member,

10 pressure means supporting said movable work-supporting member in a selected position, means for automatically relieving pressure from the work-supporting member to permit said work-supporting member to move relative to the die member as the die member and flexible work-supporting member assume relative shape-forming positions, and an adjustable automatically movable pressure-displacement means responsive to said flexible shape-forming member and movable in ratio to the flex of the flexible shape-forming member relative to the die.

15 6. A die of the class described comprising a base, a movable housing cooperating with the base, a die member anchored upon the base, piston-like means slidably mounted upon the die member and adapted to recede into the base, pressure means for resisting inward movement of the piston means into the base, means for automatically relieving pressure from the piston means at a predetermined degree, a flexible shape-forming member carried by the movable housing and adapted to engage a work sheet contacting with said die member, a means for supplying pressure to the flexible shape-forming member, and adjustable pressure-relieving means carried by said movable housing.

LEWIS E. WALTON.
